UNITED STATES PATENT OFFICE.

CALVIN L. DIVINE, OF INDIANAPOLIS, INDIANA, ASSIGNOR TO LYNN B. MARTINDALE, OF SAME PLACE.

EXTENSION COMPOSING-STICK.

SPECIFICATION forming part of Letters Patent No. 268,084, dated November 28, 1882.

Application filed July 18, 1882. (No model.)

To all whom it may concern:

Be it known that I, CALVIN L. DIVINE, of the city of Indianapolis, county of Marion, and State of Indiana, have invented certain new and useful Improvements in Extension Composing-Sticks, of which the following is a specification.

The object of my said invention is to produce a composing-stick in which the type-holding space may be extended or enlarged when required. This object is accomplished by constructing the back of the type-space separate from the sides thereof, mounting said back upon sliding bars which move in grooves in said sides, and connecting to said back a second or supplemental bottom which shall rest and be adapted to move in slides attached to the under side of the regular bottom, all as will hereinafter be more specifically set forth.

As is well known by all type-setters, the ordinary composing-stick does not hold a sufficient quantity of type to make it convenient for the workmen, a "take" of "matter" frequently more than filling it, thus necessitating the use of two sticks. A common stick cannot be made wide enough to remedy this defect, for the reason that a printer must hold the type with his thumb as he sets it, and therefore no stick can be made wider than the length of that portion of his thumb which can be utilized for this work. My invention avoids all these disadvantages and objections, as it is no wider than is desirable when the operation of typesetting is commenced, and as the stick is filled the back can be moved out, which, as the distance from the front edge of the stick to the front side of the type is not increased, is of course not objectionable.

Referring to the accompanying drawings, which are made a part hereof, and on which similar letters of reference indicate similar parts, Figure 1 is a top or plan view of my improved stick when it is in the usual form of other composing-sticks; Fig. 2, a similar view when the extension has been moved out; Fig. 3, an underside plan, the extension being shown partly out; Fig. 4, a rear side elevation, and Fig. 5 a front side elevation.

In said drawings the portions marked A A' 50 represent the ordinary non-movable portions of a printer's composing-stick; B, the usual

movable jaw, and C C' a sliding back and bottom, which, together with the slides, &c., used in connection therewith, constitute my said invention.

55

All the portions except those distinctly described and claimed as new are of the common well-known form and construction, and need no further description except such as will be incidentally given in describing the new features.

The sliding bottom C and back C' are either constructed in one piece or connected rigidly together. The bottom C moves in guides or slides *a* on the underside of the permanent bottom A, and when moved out, as shown in Figs. 2 and 3, forms an extension to said permanent bottom. The extension portions of this stick are prevented from moving back so far as to become wholly detached from the other portion by means of the small stop-arms *c*, which come in contact with the stops *a'*, which are attached to and form a part of the guides *a* when the extension has reached the limit of its intended movement. The back C' forms, 75 when closed up, as shown in Fig. 1, in effect, that portion of the regular back A' which performs the usual function of a back. When moved out it still performs the same function, and the bars *c' c'* supplement the end A² and 80 the jaw B in forming the sides to the type-space. There are dovetailed or other suitably-formed grooves in said parts A² B, which receive these bars. As will be noticed, the inner faces of the parts A² *c'* and B *c'* are in line 85 respectively, so that there shall be no disarrangement of the type when moved back into the extension formed by the parts C C' *c' c'*. The back portion, C', has a slot, *c'*, through which the end of the side bar *c'* passes, so that 90 said side bar may be permitted to move with the jaw B when the latter is moved for the purpose of adjusting or changing the length of the type-space.

The method of using my improved composing-stick is as follows: The stick is first closed up into the ordinary form, as shown in Fig. 1, and is set full of type in the ordinary manner. The type is then pushed back, carrying the extension with it, leaving room in which more 100 type is set, until it is desired to empty the stick. The extension is then pushed back to

its former position and the process repeated.

Having thus fully described my said invention, what I claim as new, and desire to secure by Letters Patent, is—

- 5 1. As a new article of manufacture, a printer's composing-stick provided with an extensible back, sides, and bottom, whereby the width of the type-space may be increased, substantially as set forth.
- 10 2. The combination of the bottom A, the non-movable end A², the movable jaw or end B, the non-movable back portion, A', and the movable back portion, C', having the bottom portion, C, and side bars, c² c³, attached thereto and adapted to move therewith, substantially as set forth.
- 15

3. The combination of the bottom A, having guides a, the end A², and jaw B, having dovetailed or similarly-formed grooves therein, the non-movable back portion, A', to which the jaw 20 B is secured, and the back portion, C', bottom C, and bars c² c³, connected together, said bottom and bars being adapted to move in said guides and grooves, substantially as set forth.

In witness whereof I have hereunto set my 25 hand and seal, at Indianapolis, Indiana, this 13th day of July, A. D. 1882.

CALVIN L. DIVINE. [L. S.]

In presence of—

C. BRADFORD,
LYNN B. MARTINDALE.
